PYRAMIDAL HORN

Alberto Birlain Schafler, Ceylan 687, Col. Industrial
Vallejo, Mexico City, Mexico

Filed Aug. 23, 1972, Ser. No. 283,150

Term of patent 14 years

Int. Cl. D21—01

U.S. Cl. D34—15 C

FIG. 1 is a side elevational view of a pyramidal horn showing my new design;

FIG. 2 is a bottom plan view;

FIG. 3 is a side elevational view partly in section showing the nozzle member; and

FIG. 4 is a bottom plan view of the nozzle member.
I claim:

The ornamental design of a pyramidal horn, substantially shown and described.
